UNITED STATES PATENT OFFICE

2,444,021

WASHING MACHINE DRIVE

John Oakley, Springfield, Mass., assignor to Perkins Machine and Gear Company, West Springfield, Mass., a corporation of Massachusetts

Application September 25, 1946, Serial No. 699,190

6 Claims. (Cl. 74—77)

1

This invention relates to improvements in driving mechanism and is directed more particularly to mechanism for oscillating the agitator shaft of a washing machine.

The principal objects of the invention are the provision of driving mechanism for oscillating a shaft, such as the shaft of a washing machine, back and forth through various angles and is characterized by means for controlling the crawl of the oscillations about the axis of oscillation.

The U. S. patent to Oakley, No. 2,388,176, of October 30, 1945, discloses driving mechanism of the type to which this invention relates. Said mechanism includes driving and driven members having complementary angularly disposed engageable faces. The driving member is reciprocated by a rotating member and is pressed against the driven member so that it is oscillated through various angles accordingly as the pressure varies. In this way that angle of oscillation may be selected which will be best suited for the material being washed and may vary from zero to a maximum which may be in the neighborhood of two hundred and ten degrees.

Under some conditions with the mechanism described, the oscillations tend to crawl around the axis of oscillation so as to wind the material being washed about the agitator or shaft and under certain other conditions the driving member operates on the same peripheral portion or portions of the driven member through practically successive cycles of operation so that the driven member becomes worn in a spot or spots.

Both conditions are objectionable wherefore according to this invention means is provided for controlling the crawl of the oscillations in such a way that when the oscillations crawl in one direction or the other, about the axis of oscillation, the crawl is reversed and at the same time the engagement of the driving member with the driven member is not limited to a particular portion of the periphery of the driven member all of which insures that material being washed will not be wound up by the agitator or its shaft and the driven member is worn, if at all, about its entire periphery.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully de-

2

scribed and referred to in connection with the accompanying drawings wherein:

Fig. 1 is an inverted plan view of a washing machine having the novel driving mechanism of the invention associated therewith;

Fig. 2 is an enlarged plan view of the mechanism for controlling the operation of the driven member;

Fig. 3 is a sectional elevational view on the line 10 3—3 of Fig. 1;

Fig. 4 is a diagrammatic plan view to explain certain features of the invention; and

Fig. 5 is a perspective view of certain components of the mechanism.

Referring now to the drawings more in detail, the invention will be fully described.

A portion of a washing machine tub is represented by 2 in an inverted position, the bottom wall thereof being indicated by 4.

A driven shaft 8 for the agitator of the washing machine extends upwardly through the bottom wall 4 of the tub and is journaled at its lower end in a housing 10. A cover is provided for the housing but is not shown. The housing may be secured to the tub in any well known manner.

A motor 14 is secured by a bracket construction 15 to the housing and has a shaft 16 which is connected by a coupling 18 to a worm shaft 20.

A shaft 22 is journaled in the housing and extends upwardly of the tub for driving a wringer at the upper side of the tub.

A worm gear 24 on said shaft 22 is in engagement with a worm 26 associated with shaft 20 whereby as the motor is in operation the shaft 22 and worm gear are rotated.

A driving member 28 is pivotally connected at 30 to the worm gear 24 and a driven member 32 is fixed to the shaft 8. The driving and driven members are provided with angularly disposed engageable faces, as shown, so that as the driving member is reciprocated back and forth the driven member is oscillated back and forth according to the pressure applied to the driving member. By varying the pressure the driven member may be oscillated through various angles.

A pressure lever 40 has a shaft 42 journaled in the housing 10 and a slide 44 is movable longitudinally of said lever. A bearing member 46 is oscillatable in the slide 44 and slidably engages the rear side of the driving member 28.

A hub 48 fixed to the shaft 42 has a spring-like member 50 fixed thereto. An operating member 52 is journaled in a bracket 54 fixed to the tub 55 and a cam 56 is carried by the inner end of the

operating lever. An adjusting bolt 58 is in threaded engagement with the outer end of member 50 and is engageable with the cam 56.

The member 50 is relatively yieldable or spring-like and as lever 52 is swung in one direction or the other the member 50 is flexed more or less so that the lever 40 acts with more or less pressure, through member 46, on the driving member 28. By varying the pressure the angle of oscillations of the driven member 32 and shaft 8 may be varied. That is, the member 32 may be oscillated from zero angle to maximum angle.

As previously stated, the oscillations of the driven member may, under certain conditions, tend to crawl around the axis of oscillation and cause material to be wound up by the shaft 8 or by the agitator carried thereby. Or under certain conditions over a period of time a certain portion of the periphery of the driven member will be engaged by the driving member so that the former becomes worn in a spot or spots.

The mechanism now to be described will control the oscillations and operation thereof in such a way that oscillations crawling in one direction will be directed in an opposite direction while oscillations may take place throughout the periphery of the driven member thereby to obtain uniform wear about the periphery thereof.

An actuator 60 disposed transversely to the axis of shaft 8 has a portion 62 journalled in said shaft. Said actuator is free to swing relative to said shaft. A bridge member 64 in the form of a U has side stop portions 66 vertically disposed and secured to the shaft 8, see Fig. 3.

A lever 68 has an intermediate portion 70 disposed above the members 60 and 64 and an outer portion 72 adjacent the driven member 32. Said lever 68 extends loosely through a bell-shaped opening of a fulcrum member 74 and has an outer portion 76 which extends downwardly through a slot 78 in the slide and is pivoted therebelow at 80 in the lever 40, see Fig. 5.

As previously stated, the member 46 is slideable longitudinally of lever 40. By moving said slide member from one position to another when the oscillations of the shaft 8 are rotating about the axis of oscillations the crawl will be directed in an opposite direction.

It will be assumed that the driving member is being reciprocated back and forth and that the pressure against said member is such as to produce the desired angle of oscillations of the driven member 32 and shaft 8.

The said angle of oscillations is represented by *a* in Fig. 4. Suppose, then, that the oscillations crawl about the axis of oscillations, say in the direction of arrow *b*. As the angle of oscillations gradually works around clockwise, one of the stops 66 of the bridge 64 abuts the actuator 60 and on a clockwise oscillation brings the actuator 60 into abutment with part 72 of lever 68. This oscillation or a succeeding one causes the actuator 60, which is backed up by stop 66, to swing lever 68 clockwise in the direction of arrow *c*. The said lever 68 being fulcrumed in member 74 and having its end 80 pivoted in lever 40 on being thus swung shifts the slide 40 to the right. This shifts the point of pressure on the driving member 28 relative to a vertical plane passing through the axis of oscillation and the oscillations may crawl in a reverse direction and opposite to that indicated by arrow *b*. Whenever the oscillations in said reverse direction carry the actuator 60 and the other of the stops 66 so that the actuator engages the part 72 of lever 68 thereby to swing

lever 68 counterclockwise the block 40 is moved to the left thereby to direct the oscillations clockwise.

In some cycles of operation or with a certain pressure applied to the driving member to obtain a certain angle of oscillations there may be no crawl or tendency of the oscillations to crawl about the axis of oscillation but there is an inherent tendency for the crawl to develop at certain pressures and angles of oscillations. By shifting the slide 40 in one direction or the other the crawl is controlled or it is directed in an opposite direction so as to overcome the objectionable winding up of the material by the shaft or agitator.

At the same time, it is desired that the driving member operate on the entire periphery of the driven member thereby to obtain uniform wear of the latter. To that end the parts of the mechanism are formed and intended whilst controlling the crawl to allow the shaft 8 to make at least one complete revolution and it may be arranged to make considerably more if desired.

In the event the shaft 8 becomes jammed against rotation since the lever is spring-like the actuator 60 on an oscillation of the shaft may engage and elevate so as to pass under the end 72 of said lever, thereby insuring against injury to the mechanism.

In some cases it may be desirable to pivot the end of member 72 in the side of housing 10 or in some part separate from member 40. The operation will be similar to that of the construction shown in Figs. 2 to 5 inc. but its action will not be influenced by different positions of member 40 or movements thereof.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. The combination of driving mechanism including an oscillatable driven member and a reciprocable driving member having angularly disposed complementary engageable faces with means for applying various pressures to said driving member to obtain varying angles of oscillation of the driven member and to control the tendency of said oscillations to crawl about the axis of oscillation comprising, a pressure member movable towards and away from said driven member and means to apply varying pressures thereto, a slide on said member bearing against said driving member and slideable back and forth relative thereto to vary the point of pressure on said driving member relative to a plane passing through the axis of oscillation of said driven member and transverse to the direction of movement of said driving member, engageable means carried by said driven member and slide adapted as the oscillations of said member crawl in one direction about the axis of oscillation to move said slide relative to said plane thereby to change the point of pressure.

2. The combination of driving mechanism including an oscillatable driven member and a

reciprocable driving member having angularly disposed complemental engageable faces with means for applying various pressures to said driving member to obtain varying angles of oscillation of the driven member and to control the tendency of said oscillations to crawl about the axis of oscillation comprising, a pressure member movable towards and away from said driven member and means to apply varying pressures thereto, a slide on said member bearing against said driving member and slidable back and forth relative thereto to vary the point of pressure on said driving member relative to a plane passing through the axis of oscillation of said driven member and transverse to the direction of movement of said driving member, engageable means carried by said driven member and slide operable when said oscillations have crawled in one direction through a predetermined angle about the axis of oscillation to move said slide relative to said plane to direct said crawl in an opposite direction.

3. The combination of driving mechanism including an oscillatable driven member and a reciprocable driving member having angularly disposed complemental engageable faces with means for applying various pressures to said driving member to obtain varying angles of oscillation of the driven member and to control the tendency of said oscillations to crawl about the axis of oscillation comprising, a pressure member movable towards and away from said driven member and means to apply varying pressures thereto, a slide on said member bearing against said driving member and slidable back and forth relative thereto to vary the point of pressure on said driving member relative to a plane passing through the axis of oscillation of said driven member and transverse to the direction of movement of said driving member, engageable means carried by said driven member and slide operable when said oscillations have crawled in one direction through a predetermined angle about the axis of oscillation to move said slide relative to said plane to direct said crawl in an opposite direction, said means adapted to permit said crawl to rotate at least one revolution about said axis of rotation.

4. The combination of driving mechanism including an oscillatable driven member and a reciprocable driving member having angularly disposed complemental engageable faces with means for applying various pressures to said driving member to obtain varying angles of oscillation of the driven member and to control the tendency of said oscillations to crawl about the axis of oscillation comprising, a pressure member movable towards and away from said driven member and means to apply varying pressures thereto, a slide on said member bearing against said driving member and slidable back and forth relative thereto to vary the point of pressure on said driving member relative to a plane passing through the axis of oscillation of said driven member and transverse to the direction of movement of said driving member, engageable means carried by said driven member and slide operable when said oscillations have crawled in one direction through a predetermined angle about the axis of oscillation to move said slide relative to said plane to direct said crawl in an opposite direction, said

means including a lever connected to said slide and an actuator carried by said driven member engageable therewith.

5. The combination of driving mechanism including an oscillatable driven member and a reciprocable driving member having angularly disposed complemental engageable faces with means for applying various pressures to said driving member to obtain varying angles of oscillation of the driven member and to control the tendency of said oscillations to crawl about the axis of oscillation comprising, a pressure member movable towards and away from said driven member and means to apply varying pressures thereto, a slide on said member bearing against said driving member and slidable back and forth relative thereto to vary the point of pressure on said driving member relative to a plane passing through the axis of oscillation of said driven member and transverse to the direction of movement of said driving member, engageable means carried by said driven member and slide operable when said oscillations have crawled in one direction through a predetermined angle about the axis of oscillation to move said slide relative to said plane to direct said crawl in an opposite direction, said means including a lever connected to said pressure member and fulcrumed on said slide and an actuator carried by said driven member engageable therewith.

6. The combination of driving mechanism including an oscillatable driven member and a reciprocable driving member having angularly disposed complemental engageable faces with means for applying various pressures to said driving member to obtain varying angles of oscillation of the driven member and to control the tendency of said oscillations to crawl about the axis of oscillation comprising, a pressure member movable towards and away from said driven member and means to apply varying pressures thereto, a slide on said member bearing against said driving member and slidable back and forth relative thereto to vary the point of pressure on said driving member relative to a plane passing through the axis of oscillation of said driven member and transverse to the direction of movement of said driving member, engageable means carried by said driven member and slide operable when said oscillations have crawled in one direction through a predetermined angle about the axis of oscillation to move said slide relative to said plane to direct said crawl in an opposite direction, said means including a lever connected to said pressure member and fulcrumed on said slide and an actuator carried by said driven member engageable therewith, said lever being yieldable so as to allow said actuator to pass therepast under certain conditions.
